UNITED STATES PATENT OFFICE

SOMERLED JOSEPH McDONALD, OF GATINEAU, QUEBEC, CANADA, ASSIGNOR TO INTERNATIONAL FIBRE BOARD, LIMITED, OF MONTREAL, QUEBEC, CANADA

WALL BOARD

Application filed December 21, 1928. Serial No. 327,708.

This invention relates to wallboard and particularly to boards which are made of compressed fibre or like material and used for forming so-called lath for supporting a 5 layer of plaster thereon. Such boards are usually rectangular and are nailed, edge to edge, to the studding of the wooden frames of buildings, a sufficient number of boards being secured in this manner to form the de- 10 sired area of wall surface.

Objects of the present invention are to provide improved boards in which the edges are so shaped that the boards mutually support one another at the regions where they are 15 not supported by the studding, and that the risk of plaster cracking along the edges of the boards is greatly reduced, and that an approximately air-tight joint is formed between the studding.

20 The invention consists in the improved formation and arrangement hereinafter described and more particularly pointed out in the appended claims.

Referring now to the accompanying drawings, which illustrate, by way of example, one convenient embodiment of the invention:

Figure 1 is a front elevation of a portion of the improved board, showing fragments of other boards engaging the edges thereof;

25 Figure 2 is a side elevation partly in section on the line 2—2 of Figure 1;

Figure 3 is a side elevation partly in section on the line 3—3 of Figure 1;

Figure 4 is a plan view of Figure 1, and

30 Figure 5 is a fragmentary section on the line 5—5 of Figure 1.

In the drawings the boards are shown with their edges slightly separated for the sake of clearness of illustration, but actually the 35 edges would be in contact in practice.

In the illustrated examples of the invention the board has flat front and rear surfaces 1 and 2, respectively, and side surfaces 3. The upper edge is formed with a V-shaped or similarly shaped groove 4 and the lower edge with a complementary tongue portion 5.

45 Preferably, the front wall of the groove 4 is recessed at suitable short intervals to provide notches 6.

50 It is also preferred to provide spaced in-

clined notches 7 and 8 in the edges at which the surfaces 1 and 3 meet. The notches 7 are displaced or staggered vertically with respect to the notches 8 an amount equal to the length of a notch, so that when one board 55 is laterally aligned with another board, the notches 8 of one board register with the unnotched portions situated between the notches 7 of the other board, as shown clearly at the left-hand side of Figure 1. Or the notches 60 might be lengthened so that the notches 8 could overlap or connect two adjacent notches 7.

It is believed that the manner of mounting the boards in relation to one another will be 65 clear from Figure 1 of the drawing, in which the four edges of a board A are shown together with the lower part of another board B and the right-hand edge of a third board C.

The number and size of the notches 6, 7 and 8 may be selected according to the size of board to be manufactured.

It will be seen that the tongue 5 of each 75 board engages the groove 4 of the next board below and the V-shaped joint thus formed enables the boards to give one another mutual support against flexure, to which ordinary butting edges would be subject at the regions where the boards are not supported by the wooden studding. This construction 80 also provides a substantially air-tight joint.

The notches 6 form a series of wedge-like recesses which provide good anchoring or bonding points for the plaster which is afterwards applied to the front surface of the wall 85 formed of the boards assembled in the manner described.

The notches 7 and 8 form two series of staggered, wedge-like recesses providing improved anchorage or bonding points for the 90 plaster.

The notches 6, 7 and 8 serve another important purpose in that, owing to their wedge-like form, they have the effect of advantageously changing the direction of the reaction 95 forces created when rearwardly directed forces are applied to a plastered wall constructed according to this invention. In a wall constructed of ordinary boards with plane butting edges, the reaction forces are 100

comparatively feeble and in such a direction that straight cracks in the plaster, along the line of the abutting edges of the boards, are readily made. In a wall made up of plastered boards according to the present invention, however, the reaction forces are such that the plaster cannot crack along a straight line, but can only crack along undulating lines which dip into the notches. As it requires a much greater force to produce such an undulating crack than a straight one, it follows that in walls made of the improved boards there is a greatly reduced liability to fracture of the plaster.

The invention is particularly applicable to boards made of compressed fibre, but may be applied to boards of other materials of a similar character.

The foregoing description and accompanying illustration are given by way of example and modifications within the scope of the appended claims may be resorted to without departing from the scope of the present invention.

I claim:

1. A wall comprising a plurality of similar substantially rectangular boards arranged edge to edge in vertical and horizontal rows, the opposed edges of the boards having tongue and grooved engagement with each other and the remaining opposed edges of the boards being straight and in abutting engagement and also having a series of equi-distant wedge-like depressions to provide binding points.

2. A wallboard comprising a substantially rectangular sheet of material having in one edge a longitudinal groove, a complementary tongue extending along its opposite edge for engagement with the groove of an adjacent board, the outer wall of the groove being recessed at intervals to the full depth of the groove to provide a series of notches which constitute binding points for plaster applied over the wallboard, the remaining opposite edges of the board being straight and having a series of wedge-like depressions spaced from each other distances equal to the length thereof with the series in one edge staggered with respect to the series in the abutting edge of an adjacent board to form additional binding posts for the plaster.

In testimony whereof I have affixed my signature.

SOMERLED JOSEPH McDONALD.
